[57] CLAIM

The ornamental design for narrow side panel for light fixture, as shown and described.

DESCRIPTION

FIG. 1 is a front perspective view of a narrow side panel for light fixture showing my new design:

FIG. 2 is a rear perspective view thereof; and

FIG. 3 is an end view thereof.

The end not shown is similar to the end shown.

The panel is broken away in FIGS. 1 and 2 to indicate indeterminate length.
